US00D901688S

(12) **United States Design Patent** (10) Patent No.: **US D901,688 S**
Thouément et al. (45) Date of Patent: **** Nov. 10, 2020**

(54) **BONE PUNCH**

(71) Applicant: **Karl Storz SE & Co. KG**, Tuttlingen (DE)

(72) Inventors: **Yann Thouément**, Guyancourt (FR); **Régis Besse**, Guyancourt (FR)

(73) Assignee: **KARL STORZ SE & CO. KG**, Tuttlingen (DE)

(**) Term: **15 Years**

(21) Appl. No.: **29/677,125**

(22) Filed: **Jan. 17, 2019**

(30) **Foreign Application Priority Data**

Jul. 19, 2018 (EM) 005507555-0001

(51) **LOC (12) Cl.** **24-02**

(52) **U.S. Cl.**

USPC **D24/146**; D24/147

(74) Attorney, Agent, or Firm — Eversheds Sutherland (US) LLP

(57) **CLAIM**

The ornamental design for a bone punch, as shown and described.

DESCRIPTION

FIG. 1 is a perspective view of a bone punch showing our new design;

FIG. 2 is a right side view thereof;

FIG. 3 is a left side view thereof;

FIG. 4 is a front view thereof;

FIG. 5 is a rear view thereof:

(Continued)

FIG. 6 is top view thereof; and,
FIG. 7 is a bottom view thereof.

1 Claim, 5 Drawing Sheets
